UNITED STATES PATENT OFFICE.

HUBERT GRUNENBERG, OF NEW YORK, AND ALEXANDER KATZ, OF UNIONPORT, NEW YORK, ASSIGNORS TO FLORASYNTH LABORATORIES, INC., A CORPORATION OF NEW YORK.

FLAVORING AND PERFUMERY EXTRACT.

No Drawing.

Application filed March 3, 1922. Serial No. 540,831.

To all whom it may concern:

Be it known that we, HUBERT GRUNENBERG, a citizen of the United States, residing in the city, county, and State of New York, and ALEXANDER KATZ, a citizen of Russia, residing at Unionport, New York, have invented certain new and useful Improvements in Flavoring and Perfumery Extracts, of which the following is a specification.

The present invention relates to flavoring and perfumery extracts.

It is customary in the preparation of extracts of the above type to use an alcoholic base, either ethyl alcohol or its higher homologues to maintain the essential oils and synthetic chemicals forming part of the extract in solution. As most of the essential oils and synthetics are insoluble in water, a high percentage of alcohol was necessary, which, of course, increased the cost of the extract. The presence of alcohol is also objected to by some on principle, and is in many cases objected to by the prohibition department.

The object of the invention is the provision of a flavoring and perfumery extract having in place of the alcohol, a satisfactory substitute. Such a substitute must be miscible with the water and a solvent for the essential oils, harmless, without any objectionable taste or odor, non-intoxicating and inexpensive.

We have found that the organic substances suitable for this purpose are obtained when glycerine enters into the chemical reaction with another compound and if two valencies of said other compound engage two hydroxyl groups of the glycerine, the elimination of the elements of water taking place in this reaction, replacing two typical alcoholic hydrogen atoms of the glycerine by certain radicles.

We have found that a process in which glycerine is acted upon by one molecule of a dibasic acid or of a diatomic alcohol, both having preferably not more than five carbon atoms in the chain of its radicle, furnishes products in the form of a cyclic glycerine di-ester and glycerine di-ether, respectively, said products being miscible with water and acting as solvents for essential oils and synthetics.

The third hydroxyl group of the glycerine is unattacked in these reactions.

Examples of cyclic esters of diatomic acids are glycerine-malonate, glycerine-succinate, and glycerine-glutinate.

Said glycerine di-esters with the cyclic chain include glycid, glycerine-ether, acetone-glycerine, ethylen-glycerine, and ethylene-glycerine, their homologues and derivatives, as for instance, methyl-acetone glycerine and propylene-glycerine.

The number of compounds within the scope of our invention is rather considerable if varied by the substitution of different acyl or alkyl radicles in the well known manner. Such compounds embrace, for instance, also the mixed mono-esters-mono-ethers.

We are aware of United States Patent No. 1,387,099 to Esselein, wherein is disclosed a flavoring extract comprising an essential oil dissolved in a mixture of mono and diacetone. In making our preparation, however, we avail ourselves of certain properties of the compounds enumerated above which could not be anticipated even if familiar with the subject matter of the Esselein patent.

We succeed, for instance, by means of said compounds to keep some of the terpenes in solution, especially oil of juniper. We have, furthermore, found that the higher acyl derivatives of glycerine are more stable than the lower ones, the alkyl ethers are absolutely stable and are perfect solvents for oils and synthetics in every respect.

Examples.

Cyclic esters: 1 oz. orange oil or any other essential oil or synthetic, 4 ozs. glyceryl fumarate, 12 ozs. glycerine or sugar syrup.

Cyclic ethers: 1 oz. rose synthetic or any other synthetic material, 4 ozs. glycid, 12 ozs. mixture of water and glycerine.

In the claims the term "essential oil" is to be understood as covering artificial essential oil or synthetic oil of this character.

We claim:

1. A solution comprising an essential oil dissolved in a glycerine compound having the hydrogen atoms of two of its hydroxyl groups substituted by a bivalent radicle and having its third hydroxyl group unattached.

2. A solution comprising an essential oil dissolved in a glycerine compound having the hydrogen atoms of two of its hydroxyl groups substituted by a bivalent radicle and

having its third hydroxyl group unattached, the carbon atoms to which aforesaid two hydroxyl groups are attached, forming a closed chain with the radicle.

5 3. A solution comprising an essential oil dissolved in a glycerine compound having the hydrogen atoms of two of its hydroxyl groups substituted by the radicle of a dibasic acid and having its third hydroxyl 10 group unattached.

4. A solution comprising an essential oil dissolved in a derivative of a di-ester of glycerine with a dibasic acid.

5. A solution comprising an essential oil dissolved in a glycerine succinate.

15 In testimony that we claim the foregoing as our invention, we have signed our names.

HUBERT GRUNENBERG.
ALEXANDER KATZ.
